Specification for Design.

Patented Mar. 14, 1922.

Application filed October 6, 1920. Serial No. 415,170. Term of patent 3½ years.

To all whom it may concern:

Be it known that I, EMMA S. FISCHER, a citizen of the United States, and a resident of Belleville, in the county of Essex and State of New Jersey, executrix of the estate of JOSEPH FISCHER, deceased, late a citizen of the United States and late a resident of Belleville, in the county of Essex and State of New Jersey, who did in his lifetime invent a new, original, and ornamental Design for a Frame for Mirrors or Similar Articles,

do declare that the following is a specification, reference being had to the accompanying drawing, forming a part thereof.

The figure is a plan view of a frame for a mirror or similar article showing my new design.

I claim:

The ornamental design for a frame for a mirror or similar article as shown.

EMMA S. FISCHER,
Executrix of the estate of Joseph Fischer.
